JAMES CROWE, OF PHILADELPHIA, PENNSYLVANIA.

FLUID-CONTROLLING MECHANISM.

1,267,982.

Specification of Letters Patent. Patented May 28, 1918.

Application filed May 25, 1917. Serial No. 170,948.

To all whom it may concern:

Be it known that I, JAMES CROWE, a citizen of the United States, residing at Philadelphia, in the county of Philadelphia and 5 State of Pennsylvania, have invented new and useful Improvements in Fluid-Controlling Mechanism, of which the following is a specification.

This invention relates to valve mechanism, and has particular reference to improved mechanism for governing the flow 10 of beer or other fluid from a supply barrel to a dispensing element.

The primary object of the invention resides in the provision of valve mechanism, 15 which is operable to be positioned within a system of piping, principally employed in conveying fermented liquor from a supply barrel to points for cooling and dispensing, 20 whereby all of the fluid contained in said barrel will be withdrawn therefrom and utilized, and undue waste thereof eliminated.

With this and other objects in view, as 25 will appear as the description proceeds, the invention accordingly consists in the novel features of construction, combination of elements and arrangement of parts herein-after fully described, and set forth with 30 particularity in the appended claims.

In the drawings—

Figure 1 is a side elevation of the mechanism comprising the preferred form of the present invention, illustrating the same as 35 associated with fluid containing barrels and cooling coils.

Fig. 2 is a vertical sectional view taken through the valve receptacle, and

Fig. 3 is a horizontal sectional view taken 40 along the line 3—3 of Fig. 2.

Similar characters of reference denote corresponding parts throughout the several views of the drawings.

Hitherto considerable difficulty has been 45 encountered in withdrawing the full contents of a barrel of beer or the like, due to the fact that when the fluid contained by the barrel reaches a low level it becomes frothy in quality, so that it cannot be 50 properly forced through the usual discharge pipes by pneumatic pressure, this being due to the fact that the body thereof is not sufficiently dense to enable the fluid to withstand air pressure so as to retain its normal 55 condition. Thus under present conditions it is necessary to discard the barrel before

all the fluid contained thereby is utilized, and this results in a waste of fluid varying from one-half gallon to one gallon, in a barrel having a capacity of approximately 60 30 gallons.

In order to obviate this waste, and to provide means for completely draining a barrel of its contents, I employ a novel 65 form of valve mechanism 1, which includes a receptacle 2, of bronze or the like, having an annular flange 3 formed upon the upper edge thereof. A top plate 4 is bolted or otherwise secured to the flange, and a gasket is interposed between the flange and plate 70 to provide a leak-proof joint. An inflow pipe 5 is carried by the plate 4 and extends vertically within the receptacle, said pipe terminating immediately adjacent to the bottom 6 of the casing. The upper extremity of the pipe 5 is provided with an enlarged head 7, resting upon the exterior surface of the plate 4, and a Y-shaped pipe 7' is secured to the said upper extremity of the pipe 5 by means of a threaded nut 8. 80 The branched extremities of the pipe 7' are provided with valves 9, and are provided with communicating pipes 10 which lead to vertically arranged pipes 11. The latter are adapted to extend, as usual, into bungholes 85 12 provided in fluid-containing barrels 13 and terminate adjacent to the bottoms of the latter. Thus when the valves of the pipes 7' and 11 are open, fluid will flow 90 from the barrels 13 to the receptacle 2, this being accomplished by the action of air under pressure pressing upon the body of the fluid contained within the barrels 13, as is usual and well understood. Ordinarily fluid will only flow from one of the 95 barrels 13, not both, so that when one of the barrels is empty fluid will be conveyed to the receptacle 2 by opening the valves controlling the flow of fluid from the other barrels. The plate 4 also carries an air- 100 escape valve pipe 14, which permits of the release of air from the receptacle when the latter is being filled with a suitable fluid.

An outlet pipe 15 protrudes into the receptacle 2, and is disposed in parallel relation to the pipe 5, the pipe 15 being retained in place within the receptacle by being suitably secured to the top plate 4. The lower extremity of the outlet pipe is provided with an upwardly-bent neck 16, which 110 terminates adjacent to the bottom 6 of the receptacle, and is provided with an enlarged

- valve seat 17. Spaced brackets 18 are adjustably carried by the pipe 15, and are provided with suitable bearings for the reception of a vertically movable valve stem 19.
- 5 The lower extremity of the stem 19 is provided with a valve 20, which is adapted to open and close the seat 17. A float 21 of cork or the like is carried by the stem 19, and is utilized to automatically open and 10 close the valve 20, in accordance with the amount of fluid contained by the receptacle.

When the receptacle 2 becomes substantially filled with fluid received from one of the barrels 13, it will be seen that the valve 15 20 will be lifted by the floating action of its stem 19, thus permitting fluid to be withdrawn from the receptacle by way of the outlet pipe 15. A valve and branched pipe element 22 is connected with the upper extremity of the outlet pipe and from which leads piping 23, the latter being associated with the usual cooling coils 24, commonly found in beer-distributing systems. A valve vent pipe is provided in the bottom 6 of the 25 receptacle, and is employed to drain fluid from the latter at suitable periods.

In operation, when the fluid within the receptacle 2 begins to lower, the valve 20 will immediately close, thus preventing said 30 fluid from being withdrawn from the receptacle. This permits the relatively frothy fluid remaining in one of the barrels to be transferred to the receptacle, whence it will be permitted to settle so as to assume its 35 proper liquid form or density, thus permitting the entire contents of the barrel to be withdrawn from the barrel and deposited within the receptacle 2, instead of being blown in a frothy state through the dispensing piping 23. When one barrel has 40 been emptied the connections between the same and the receptacle 2 are closed by means of the valves carried thereby, and a second barrel is then thrown into operation 45 by opening the valves in the connections extending from the same to the receptacle, thus enabling the said receptacle to be again filled with fluid to permit of the opening of the valve 20, as will be clearly understood.

From the foregoing it is seen that there is provided a device wherein the objects of the present invention have been achieved, and that all of the advantageous features above 50 mentioned are, among others, present. The

mechanism is relatively simple in construction, of few parts and therefore not likely to become out of order, the same can be cheaply manufactured and installed, with a minimum expense.

60

Having described the invention what is claimed as new and patentable is:

1. In fluid controlling mechanism of the class described, the combination with a source of fluid supply, of a closed receptacle, 65 a valved pipe extending from said fluid supply into said receptacle and terminating adjacent the bottom thereof, an outlet pipe extending into said receptacle and provided at its lower end with a valve seat, a valve engageable with said seat, and a float associated with said valve operable to open and close said outlet pipe when fluid within said receptacle reaches predetermined levels, said valve and float mechanism being arranged 70 exteriorly of said outlet pipe.

2. In fluid-controlling mechanism of the class described, the combination with a source of fluid supply, of a valve receptacle, a valve inlet pipe extending from said fluid supply to a position within said receptacle and terminating adjacent to the bottom of the latter, an outlet pipe having portions thereof positioned within said receptacle, and terminating in an upwardly-bent neck, 80 located adjacent to said bottom, and a float-actuated valve operable to open and close the neck of said outlet pipe when fluid within said receptacle reaches predetermined levels.

85

3. In fluid controlling mechanism of the class described, the combination with a source of fluid supply, of a receptacle, a valved inlet pipe extending from said fluid supply to within said receptacle and terminating adjacent the bottom thereof, an outlet pipe having portions thereof positioned within said receptacle, and terminating in an upwardly bent neck adjacent the bottom of the receptacle, guide brackets secured on 95 said outlet pipe, a rod slidable through said brackets, a valve on the lower end of said rod engageable upon the end of said neck, and a float secured to said rod whereby said valve will be operated to open and close said neck when fluid within said receptacle reaches predetermined levels.

100

In testimony whereof I affix my signature.

JAMES CROWE.
